UNITED STATES PATENT OFFICE.

THOMAS BELL, OF CATSKILL, NEW YORK.

ELEVATOR.

SPECIFICATION forming part of Letters Patent No. 313,162, dated March 3, 1885.

Application filed November 26, 1884. (No model.)

To all whom it may concern:

Be it known that I, THOMAS BELL, a citizen of the United States, residing at Catskill, county of Greene, and State of New York, have invented certain new and useful Improvements in Elevators, fully described and represented in the following specification and the accompanying drawings, forming a part of the same.

10 This invention relates, generally, to that class of elevators which are employed in handling coal, grain, and other similar substances, but more particularly to an apparatus of this class which is designed and adapted for use in transferring coal, grain, &c., from the cars or boats in which it is transported in bulk to a bin or warehouse.

15 As a full knowledge of the invention and its mode of operation can be imparted only by a detailed description of the apparatus in which it is embodied, all further preliminary description will be omitted, and a detailed description of said apparatus will now be given, reference being had to the accompanying drawings, in which—

20 Figure 1 is a side elevation of an elevator embodying the invention, the adjusting apparatus being omitted. Fig. 2 is a plan view of the same, showing also the adjusting apparatus. Fig. 3 is an enlarged side elevation of the adjusting apparatus. Fig. 4 is a cross-section, upon a like scale, taken upon the line $x\ x$ of Figs. 1 and 2. Fig. 5 is a plan view, upon a still larger scale, showing several of the buckets and portions of the endless chains by which they are carried. Fig. 6 is a side elevation of the same, showing also a portion of one of the sprocket-wheels which support the chains; and Fig. 7 is a cross-section of one 25 of the buckets, taken upon the line $x\ x$ of Fig. 5.

25 Referring to said drawings, it is to be understood that A represents a barge or canal-boat which is to be unloaded, and B a bin or warehouse into which the contents of the boat are to be transferred. The elevator by which this transfer of the contents of the boat is effected consists, essentially, of a series of buckets, 29, which are of substantially the usual 30 form and construction, and are secured to a pair of endless carrying-chains, 50, which

travel upon and around a number of sprocket-wheels, 40, the shafts 39 of which are supported in bearings 38, secured to the side rails, 90, of an inclined frame which extends from 55 the point of supply to the point of discharge. This frame is provided with a number of cross-shafts, 35, which are mounted in suitable bearings, 36, secured to the side rails, 90, and provided at their ends with small wheels or rolls 60 37, which rest upon inclined rails 95, which form tracks or ways for the rolls and are supported by a suitable frame-work, (represented in the drawings by the upright posts 96.) By reason of this construction the frame which 65 supports the carrying-chains and the buckets can be moved up and down along the tracks 95, as indicated by the dotted lines at the left of Fig. 1, so as to vary the height of the lower or receiving end of the elevator. This is a 70 feature of considerable importance, as it affords means by which the position of the lower or receiving end of the elevator can be raised and lowered, so as to accommodate it-self to the position of the boat A as the latter 75 is raised and lowered by the ebb and flow of the tide or by other cause, and also to bring it into such position that the buckets will be filled as the contents of the boat or other receptacle is gradually lowered.

75 The required adjustment of the frame carrying the chains and buckets is effected by means of the following apparatus: The side rails, 90, are provided upon their under sides with racks 25, which are engaged by gears 26, 80 mounted upon a shaft, 27, which is supported in bearings 28, secured to the under sides of the ways 95, as best shown in Fig. 4. The shaft 27 is provided at one end with a gear, 20, which is engaged by a small gear, 21, 85 mounted upon a shaft, 22, which is supported at one end in a pivotal bearing, 15, mounted upon the rail 95, and at the other in a movable bearing, 17, mounted in a suitable framework, 23. The shaft 22 is also provided with 90 a large friction-wheel, 24, which engages with a like wheel, 14, of smaller size, which is mounted upon a shaft, 13, which is journaled in suitable bearings, and is provided with a sprocket-wheel, 34, which is connected 95 to a drive-chain, 42, with a similar wheel, 43, mounted upon the main driving-shaft 44,

from which motion is communicated to the chains carrying the buckets. The frame 23 is provided, just beneath the wheel 24, with a curved shoe, 45, which is so positioned that 5 when the wheel 24 is in its normal position it will rest on the shoe and be prevented from turning by reason of the frictional contact therewith. The end of the shaft 22, upon which the wheel 24 is mounted, extends slightly 10 beyond the frame 23, and is arranged to be acted upon by a lever, 46, which is fulcrumed at one end to the frame 23, and is connected at its other end to a rope or chain, 47, which passes over a pulley, 48, and extends either to 15 the receiving end of the elevator or to any other convenient point from which it may be desired to operate the adjusting apparatus.

The operation of the adjusting apparatus just described will be hereinafter fully explained. 20

In addition to the capability of being adjusted bodily or as a whole, as hereinafter stated, it is very desirable in an apparatus of this class that the lower or receiving end 25 should be capable of an independent adjustment, so that it may always be brought into the position most convenient for filling the buckets. To effect this the side pieces, 90, of the frame which carries the carrying-chains 30 and buckets are made in two parts, their lower ends, which extend beyond the ways 95, being connected to the upper ends by hinges 16, as best shown in Fig. 1, so as to be capable of being swung up and down and in and out, to 35 bring the lower or receiving end of the apparatus to different positions, as indicated by the dotted lines at the left of said figure, the chains 50 being of course made of sufficient length to permit such movement. This is also 40 a feature of great importance, particularly when the elevator is used for unloading boats, as it not only permits the receiving end of the apparatus to be swung in and out, so as to reach all parts crosswise of the boat or car, 45 but also permits the apparatus to accommodate itself to any slight rising and falling or rocking motion which may be given to the boat by the wind or waves.

The lower ends of the side pieces, 90, are provided with guard bands or plates 41, which extend downward and inward beyond the line of the buckets, so as to protect the latter by keeping them from coming into contact with the bottom of the boat or other obstruction, 55 which would be liable to break or damage them.

The endless chains 50, which carry the buckets, are of substantially the common construction, consisting, as best shown in Fig. 5, of alternate single and double links. The teeth upon the wheels 40 are so arranged that they enter the openings between the two bars of the alternate double links, and thus guide and support the chains in the common manner. 60 The buckets, which, as before stated, are of the common form and construction, are made of sheet or cast metal, and are secured to the

chains by means of bolts or rivets which pass through the inner bars of the double links, all as clearly shown in Figs. 5, 6, and 7.

70

In elevators of this class as heretofore constructed it has been customary to drive the chains which carry the buckets by applying the power to the shaft of the sprocket-wheels around which the chains passed at the upper 75 end of the apparatus. When, however, as in the present case, the elevator is made adjustable as a whole, this manner of driving the chains becomes impracticable. In the present case, therefore, the driving-shaft 44 is located at some distance from the ends of the side rails, 90, and is mounted in bearings 49, which are supported upon the track-rails 95, so as to permit the rails 90 to be moved up and down to different positions without interfering with the driving apparatus. The shaft 44 is provided with a pair of sprocket-wheels, 51, which are similar to the wheels 40, and engage with the chains 50 in the usual manner, and also with a sprocket-wheel, 33, around 80 which passes a drive-chain, 52, which receives motion from any convenient source of power.

In order to hold the chains 50 in engagement with the wheels 51, there are provided a pair of sprocket-wheels, 30, which are mounted upon a shaft, 31, supported in brackets 32, secured to the track-rails 95, and located in such position as to hold the chains 50 tightly against the driving-wheels 51. 95

In order to conveniently adjust the lower 100 swinging end of the elevator, and in order also to prevent it from being drawn inward by the pressure of the buckets against the contents of the boat or car as they are being filled, the lower end of the hinged portion will be 105 connected to a rope or chain, as 53, which will pass over a pulley in the horizontal arm of a crane or similar contrivance and be controlled by a windlass, as 54, by which the receiving end of the elevator can be swung to any desired position. The windlass 54 will be provided with a holding pawl and ratchet, as 12, which will act to retain the end of the elevator in any position to which it is moved. 110

The operation of the elevator just described 115 is as follows: While the boat or car which is to be unloaded is being brought into position, the lower hinged end of the elevator will be swung up out of the way, after which it will be lowered, as shown in Fig. 1, so that its receiving end will enter the hold of the boat or car. The driving-wheels 51 will then be set in motion, so as to start the chains carrying the buckets. As the contents of the boat or car are lowered in the process of unloading, or if 120 the tide falls, so as to make it necessary to lower the receiving end of the elevator, the rope 47 will be drawn upon, so as to ease the pressure of the wheel 24 upon the shoe 45, and thus permit the elevator by its own weight to 125 slide downward along the track-rails 95. As soon as the elevator has been sufficiently lowered the wheel 24 will be allowed to fall back onto the shoe 45, where its weight will afford 130

sufficient friction to hold the elevator in place. If, from the rising of the tide or for other reason, it becomes desirable to raise the receiving end of the elevator, the rope 47 will be drawn up-
5 on, so as to raise the wheel 24 into engagement with the wheel 14, and thus start the shaft 27, and through the gears 26 and racks 25 move the elevator upward along the track-rails 95 until it has been sufficiently raised, when the
10 wheel 24 will be allowed to fall back onto the shoe 45.

In order to reduce the power required to move the elevator upward along the ways 95, and also to lessen the strain upon the adjusting and holding apparatus, one or more counterbalancing-weights, as 97, will preferably be provided, which weight or weights will be so arranged and adjusted as to nearly overcome the weight of the elevator. As the contents
15 are removed from one side or part of the boat or car, the windlass 54 will be operated so as to swing the receiving end of the elevator in or out, to bring it to a different position cross-
20 wise of the boat or car, and this will be con-
tinued until the contents of the boat or car are
25 entirely removed.

In conclusion, it is to be remarked that the construction of the apparatus may be modified in many of its details without departing from
30 the essential features of the invention.

The side rails, 90, of the frame which supports and carries the chains and buckets, instead of being arranged between the ways 95, may be arranged directly above the ways, in
35 which case the shafts 35 may be omitted, the rolls 37 being mounted in bearings secured either to the under sides of the rails 90 or the upper sides of the ways 95. The mechanism for moving or adjusting the frame carrying
40 the chains and buckets may also be different from that shown without departing from the invention, it being immaterial what particular form of mechanism is employed for this purpose so long as some convenient and suitable
45 form of mechanism is provided by which the movement of these parts can be effected.

The power, instead of being applied to the shaft 44 by means of a drive-chain and sprocket-wheel, may be applied by means of
50 a belt and pulley, or by any other suitable means, and a belt and pulleys may be substituted for the chain and wheels 42 43 34. So, also, the apparatus for raising and lowering and holding the lower swinging end of the
55 elevator may be of a different form from that shown without departing from the invention.

In some cases, where the elevator is of small size or the load light, belts may be employed in place of the chains 50 for carrying the
60 buckets, and therefore belts are to be regarded as the equivalent of the chains for this purpose.

What I claim is—

1. The combination, with the stationary in-
65 clined track-rails 95, of the movable inclined

frame supported thereon, and extending from the point of supply to the point of discharge of the elevator, the endless chains 50, carrying the buckets, and passing around wheels mounted upon the movable frame, and adjusting mechanism for moving the frame carrying the chains and buckets along the track-
70 rails, so as to raise and lower the receiving and discharging ends of the elevator, substantially as described.

2. The combination, with the stationary in-
clined track-rails 95, of the movable inclined frame supported thereon, and extending from the point of supply to the point of discharge of the elevator, the endless chains 50, carrying the buckets, and passing around wheels mounted upon the movable frame, an adjusting mechanism for moving the frame carrying the chains and buckets along the track-
80 rails, so as to raise and lower the receiving and discharging ends of the elevator, and the counterbalancing weight or weights 97, sub-
85 stantially as described.

3. The combination, with the stationary in-
clined track-rails 95, of the movable inclined frame supported thereon, and extending from the point of supply to the point of discharge of the elevator, the endless chains 50, carrying the buckets, and passing around wheels mounted upon the movable frame, and adjusting mechanism for moving the frame carrying the chains and buckets along the track-
90 rails, so as to raise and lower the receiving and discharging ends of the elevator, and the stationary driving-wheels 51, substantially as de-
95 scribed.

4. The combination, with the stationary in-
clined track-rails 95, of the movable inclined frame supported thereon, and extending from the point of supply to the point of discharge of the elevator, said movable frame extending at its lower end beyond the ends of the track-rails, and being jointed, so that the receiving end of the elevator can be swung to different positions, the endless chains 50, car-
100 rying the buckets, and passing around wheels mounted upon the movable frame, and adjusting mechanism for moving the jointed frame carrying the chains and buckets along the rails, so as to raise and lower the receiving and dis-
110 charging ends of the elevator, substantially as described.

5. The combination, with the movable in-
clined frame carrying the chains and buckets, said frame being jointed, so as to permit the receiving end of the elevator to be swung to different positions, of the guard plates or bands
120 41, substantially as described.

In testimony whereof I have hereunto set my hand in the presence of two subscribing
125 witnesses.

THOMAS BELL.
